UNITED STATES PATENT OFFICE

ELI N. CUTLER, OF WATERBURY, CONNECTICUT, ASSIGNOR TO SCOVILL MANUFACTURING COMPANY, OF WATERBURY, CONNECTICUT, A CORPORATION OF CONNECTICUT

VANITY CASE

Application filed August 31, 1931. Serial No. 560,302.

This invention relates to certain improvements in small cases or boxes for holding cosmetics, which have now become generally known in the art as vanity cases.

5 These boxes or cases are used for carrying cosmetics, such as rouge or powder, and to serve their purpose must be small, so that they can be readily carried in a pocket or hand-bag of the user and must be of attractive appearance to be saleable.

In certain types of these boxes, the box is designed to be used once and then discarded, that is, after the powder or other cosmetic has been used up, the box is thrown away.

15 Such boxes, however, must be provided with a reflecting surface so that the user can apply the cosmetic as desired. In these boxes, designed for use only as long as the original powder content lasts, cheapness in manufacture is very important as such boxes are sold at a low price and the boxes must be so constructed as to be cheaply made and assembled, so as to afford a margin of profit to the maker.

25 Such boxes, therefore, must be of as few parts as possible and such boxes so arranged as to be readily and quickly assembled.

It is the especial object of the preferred invention to provide a small vanity box or 30 case capacitated to hold cosmetics such as a powder compact and a mirror, with a simple and effective means for holding the mirror in place, such mirror holding means also acting as a hinge for uniting the body and the cover of the box.

With this and other objects not specifically referred to in view, the invention consists in certain novel parts, arrangements and combinations, which will be described in connection with the accompanying drawing and the novel features pointed out in the claim hereunto annexed.

In the drawing:

Figure 1 is a face view of a box and case 45 embodying the invention, the parts being shown in open position, and

Figure 2 is a sectional view of the case shown in Figure 1, the view being taken on line 2-2 of that figure.

50 Referring now to the drawing in detail,

the box selected to illustrate the invention is a circular box, although it will be understood that the invention is not to be restricted to this particular shape. The box shown, however, comprises a body 1, having a peripheral side wall 2. The particular box shown is capacitated to carry a cosmetic shown in the form of a powder compact marked 3, which is secured in the body of the box in any suitable manner, as for instance, by mounting it into the bottom, which is provided with ridges 4 which act to secure the compact in place.

Pivots associated with this box is a cover 5 having a peripheral flange 6 which is adapted to frictionally engage within the wall 2 of the box body 1. The flange 6 of the cover is extended to form a peripheral bead 7, and seated in this bead is a reflecting surface shown in the form of a polished metal 55 disk 8.

According to the invention, a simple means is provided for pivotally associating the body and the cover, which also acts to hold the mirror securely in the bead. In the 60 particular construction shown for effecting this purpose, this means is a single spring wire 9 which is snapped into the groove or 65 bead over the face or top of the mirror 8 and acts to hold the mirror securely in place. 70

This wire extends substantially around the groove and passes through a hinged knuckle 10 which is conveniently formed by bending over a projecting portion formed on the side wall 2 of the body 1. The cover 80 is cut away as indicated at 11 to receive this turned over portion through which the pintle wire passes, as clearly shown in Figure 1 in dotted lines.

With this construction, only four parts are required to produce a vanity case or box having a body, a cover, a mirror and means for holding the mirror in place and hinging the body and the cover together, so that a small box of attractive appearance may be 85 cheaply produced.

If desired, a catch may be provided for holding the body and cover in closed relation, such catch being conveniently produced by forming a nib 12 in the wall 2 of the box 95 100

which cooperates with a slot 13 formed in the flange 6 of the cover.

It will be seen that a very simple, effective construction for producing a vanity case or box, capacitated to hold the cosmetic has been produced by the present invention, and while the invention has been shown in its preferred form, it will be understood that certain variations may be made in the shape and in the specific construction of the box without departing from the invention as defined in the appended claim.

What is claimed is:

In a vanity case, a body capacitated to hold a cosmetic and having a peripheral wall, a projection on the wall bent to form a hinge knuckle, a cover having a peripheral wall formed with a bead or groove, a mirror in the cover substantially the size thereof and a single spring wire seated in and extending around the groove engaging substantially the whole periphery of the mirror and locking it in place and passing through the hinge knuckle for pivotally associating the cover and body, and means for holding the body and cover in closed relation.

In testimony whereof, I have hereunto set my hand.

ELI N. CUTLER.
